UNITED STATES PATENT OFFICE

CHARLES WALTER PETTMAN, OF SYDNEY, NEW SOUTH WALES, AUSTRALIA

ENVELOPE MACHINE AND THE LIKE

Application filed March 22, 1929, Serial No. 349,155, and in Australia March 14, 1928.

As a means of facilitating the opening of envelopes it has been proposed to secure a thread or cord by gum or other adhesive substance on the inside of the envelope along the 5 crease formed by folding over the flap. The object of this invention is to provide efficient mechanical means for so applying and securing such thread or cord. The invention may be carried out as a complete unit in itself, as 10 an attachment to envelope machines of known construction, or embodied as a part of such envelope machines, the construction and arrangement of the mechanism constituting my invention being such that the speed at which 15 envelopes are made is not retarded.

In the ordinary process of the manufacture of envelopes, the envelopes are formed and gummed in the machine proper and are then placed in the dryer, which is usually attached to the back of the machine. This 20 dryer consists of a framework carrying a continuous belt of chain links of special construction, the envelopes being held between each pair of links and caused to travel around 25 the dryer back to the front of the machine, by which time the gum is sufficiently dry to permit of packing. It is during the travel of the finished envelope along the dryer that the thread is placed and secured in position in 30 the envelope.

In order that the invention may be fully understood I will now describe it, reference being made to the accompanying drawings, in which

- 35 Fig. 1 is a side elevation (broken).
- Fig. 2 is a plan (broken).
- Fig. 3 is an end elevation.
- Fig. 4 is a part side view.
- Fig. 5 is a part plan.
- 40 Fig. 6 is a part elevation.
- Fig. 7 is a part side elevation.
- Fig. 8 is a part plan.
- Figs. 9, 10, 11, 12, 13, 14, 15, 16, and 17 are views of various details.
- 45 Figs. 3 to 17 inclusive are to a scale greater than that of Figs. 1 and 2.

In the description which follows, the invention will be described as if it were built into step-by-step delivery envelope making 50 machines. Its adaptation for use on other

types of dryers will be understood without further description.

The dryer consists of two side cheeks A held together by distance bolts A¹. These cheeks A have formed on their inner sides a track A² for the chain A³, which is formed in the usual manner excepting that it has a notch A⁴ in the bottom for the reception and correct positioning or registration of the envelope placed therein for a purpose as will be hereinafter mentioned. The chain A³ is driven in a step by step motion by a sprocket wheel A⁵ formed on the shaft A⁶, to which shaft is attached a ratchet wheel A⁷, which is operated by a ratchet rod A⁸ and eccentric A⁹ mounted on the shaft A¹⁰. This shaft A¹⁰ is driven direct or through gearing from the envelope machine and so timed that the positioning of the openings between the links of the chain A³ coincide with the operation of the machine.

The envelopes are guided in their passage around the dryer by guide rods A¹⁴ carried by brackets A¹⁵, suitable means of adjustment being provided to accommodate different sized envelopes.

Secured on the shaft A¹⁰ is a cam B, which causes a lever B¹ to oscillate on its pivot B². At its other end the lever B¹ is arranged to operate a slide or carriage B³ slidable or running on ball or other bearings in guides B⁴. The carriage B³ is formed with or carries a pick-up or thread arm B⁵ formed and arranged so that it may be moved back and forth across the path of and between the body and flap of each envelope, the links of the envelope carrier or chain A³ being formed with the notches A⁴ to facilitate this operation. The thread arm B⁵ has a fixed hooked jaw B⁶ and a movable jaw B⁷ attached to the stem B⁸. The two jaws B⁶ B⁷ are normally kept together by a spring B⁹, but a projection or shoulder B¹⁰ on the tail end of, or where found most convenient on the stem B⁸ is arranged to engage a stop B¹¹, which thereby causes a separation or opening of the jaws B⁶ B⁷ just before the completion of the forward travel of the stem B⁸. The jaws close again when the shoulder B¹⁰ ceases to make

contact with the stop B^{11} on the return movement of the stem B^8 .

At the side of the machine opposite to that on which the thread arm B^5 is carried is the thread carrier. This consists of a vertical spindle C carried in bearings C^1 and capable of certain partially rotatable movements by an arm C^2 secured thereon and having a pin and roller C^3 , which project into and are operated by a cam track C^4 cut or formed for that purpose in the carriage B^8 . The spindle C is provided at the upper end with two bosses $C^5 C^6$, between the upper ends of which the thread arm B^5 is projected at the end of its forward stroke. One boss C^6 carries a guide sheave C^7 for the thread or cord, the spring C^8 on the stem C^9 being provided to keep the sheave C^7 on the boss C^6 , and the other boss C^6 carries a movable jaw C^{10} on a stem C^{11} , which slides vertically in the boss C^6 . The jaw C^{10} , formed on the stem C^{11} , is normally kept closed by the spring C^{12} , but it is opened at certain times by the upward movement of a disc C^{13} slidable on the spindle C when actuated by the lever C^{14} , which is, in turn, operated by the cam C^{15} through the medium of the tappet C^{16} slidable in the bracket C^{17} . Clearance C^{18} is provided between the bottom of the stem C^{11} and the disc C^{13} to provide lost motion. The function of this thread holder is to hold the cotton in position for the thread arm B^5 to pick it up and to re-grip the cotton before it is severed so as to be ready to present it to the threading arm again at its next operation. The operation is as follows:— When the thread arm B^5 moves over to pick up the cotton, the thread holder moves the cotton at right angles to the path of the arm B^5 in position for it to be picked up. The cotton, in this position of the machine, passes around the sheave C^7 and is held by the jaw C^{10} . Immediately the thread arm B^5 has gripped the cotton and started on its return journey, the jaw C^{10} is opened to release the end. As the thread arm B^5 moves back, the thread holder gets a partial rotation by means of the arm C^2 and pin C^3 and cam track C^4 in the carriage B^8 . This partial rotation moves both the jaw C^{10} and sheave C^7 out of the path of the gummed cotton and they remain in this position until near the end of the travel of the thread arm B^5 , when a still further rotation is given to the thread holder to move the jaw C^{10} into position to grip the cotton before it is severed.

Between the reel carrier and tension device, through which the thread or cord passes in order that the thread may be kept reasonably taut, and the thread holder just described a gum or adhesive liquid bath D is placed immediately beneath the thread or cord as it is stretched to the jaw C^{10} . The reel carrier and tension device, which are of

ordinary construction, are not shown in the drawings. The thread or cord is gummed in sections just the width of the envelope, leaving dry spaces between the sections for the various mechanisms to handle it without getting gummed up. This bath D is placed so that the gummed section is pulled through the envelope and positioned so that it exactly coincides with the envelope. The gumming bar D^1 , the exact width of the envelope, is provided in the bath and is pivoted at D^2 , being caused to rise up out of the bath D to meet the underside of the thread or cord. Connected to the gumming bar D^1 by links D^3 are presser feet D^4 operating on the outside of the bath D to press the thread firmly into contact with the gumming bar D^1 . The operation of the gumming bar D^1 and attendant parts is timed and actuated through the rod D^5 , lever D^6 , and cam D^7 .

The lever E , which is formed on the end with a finger E^1 , is arranged on each side of the envelope carrier and is, by the action of the cam E^2 and tappet E^3 caused to press against the thread or cord in the crease of the envelope, after it has been drawn into position, the pressure being slightly eased before the finger E is finally lifted clear thereof. The cam E^2 is secured on the shaft F , which is operated from the main shaft A^{16} through the skew gears F^1 .

The gummed cotton having been pressed into the crease or fold of the envelope, the ends are severed by the scissors or snips G mounted on the levers G^1 and actuated at the correct time by the cams G^2 mounted on the cam shafts F , the levers G^1 being pivoted on a fixed part of the machine or bracket carried thereby. The scissors or snips G are operated to cut the thread by the links G^4 attached at one end to a fixed point G^5 and at the other to the legs of the snips G .

As it is possible that, in some instances an envelope may not be placed in the spaces in the envelope carrying chain, the following mechanism is provided to prevent the gummed thread or cord being pulled across the machine and on being cut off to fall into the chain and subsequently soil an envelope placed in the particular space:—

At the end of the cam shaft F is placed a cam H , which imparts a rocking motion to a lever H^1 through the tappet H^2 . The lever H^1 is attached to an overhead shaft H^3 . To the shaft H^3 is attached a second lever H^4 having at its outer end a V shaped groove H^5 . The tappet H^2 actuates the lever H^1 through a light spring H^6 , a stronger spring H^7 being provided to keep the tappet H^2 in contact with the cam H . When an envelope in the chain carrier comes to rest in a position for the thread or cord to be placed in the crease thereof, it will be directly underneath the groove H^5 in the lever H^4 . The cam H immediately raises the tappet H^2 , which, through

the spring H^6 , rocks the lever H^1 , shafts H^3 , and lever H^4 , further movement thereof and of the lever H^1 being arrested when the groove H^5 comes into contact with the envelope, and the tappet H^2 passes through the lever H^1 and the spring H^6 will be compressed for the rest of the movement of the mechanism. If, however, there is no envelope in the chain at the time, the lever H^4 will continue its movement and the spring H^6 will not be compressed.

Attached to the shaft H^3 is a cam sector H^8 having formed thereon a stop H^9 . Held against this sector H^8 is a cam roller J mounted on the upper end of a lever J^1 . To the lower end of the lever J^1 is pivoted a slide J^2 adapted to slide between the underside of the lever C^{14} and the upper end of its actuating tappet C^{16} . The slide J^2 has an aperture J^3 formed therein.

The sheave C^7 of the thread holder is mounted on the stem C^9 in such a manner that it is capable of vertical movement, the spring C^8 normally holding it in its lowermost position. When in this position the cotton will be held below the path of travel of the thread arm B^5 . At its lower end the stem C^9 rests upon the disc C^{13} . The stem C^{11} of the jaw C^{10} has a certain amount of lost motion between it and the disc C^{13} , as shown, clearance C^{18} being provided between the stem C^{11} and disc C^{13} . The cam C^{15} is formed with two rises.

The operation of this portion of the mechanism is as follows: If an envelope is in position in the envelope carrying chain, the lever H^4 will be arrested in its travel, consequently the cam H^8 will not travel sufficiently far to bring the step H^9 thereon under the cam roller J . The lever J^1 , therefore, will not be actuated. The slide J^2 will remain interposed between the lever C^{14} and its tappet C^{16} . Motion of the tappet C^{16} will, therefore, be transmitted to the lever C^{14} and disc C^{13} . The first rise in the cam C^{15} will raise the sheave C^7 so as to bring the cotton within the path of travel of the thread arm B^5 and it will be picked up thereby while the jaw C^{10} will remain shut owing to lost motion due to the clearance C^{18} . The second rise in the cam C^{15} will raise both sheave C^7 and jaw C^{10} still higher to open the jaw C^{10} to release the cotton.

Should no envelope be in place, the lever H^4 will continue its movement and will bring the step H^9 under the cam roller J , causing the lever J^1 to rock. The slide J^2 , being pivoted to the bottom end of the lever J^1 , will be moved to bring the aperture J^3 over the end of the tappet C^{16} , into which aperture the tappet will work when actuated by the cam C^{15} and no movement will be communicated to the lever C^2 , consequently the sheave C^7 will not be raised to bring the cotton into line with the thread arm B^5 and the jaw C^{10} will not be opened to release the cotton. The various

cams, which are carried on shafting suitably placed and driven, are shaped so as to give the desired movement to the various levers and other moving parts, while the speed of rotation is such as will enable the various parts to co-act in proper relationship not only one with the other but also with the parts of the envelope making machine.

The operations of the various sections of the mechanism have already been described. The operation of the machine as a whole is such that the thread or cord is drawn from a reel through a suitable tension, and a section the length of the envelope is gummed. The thread or cord is then drawn forward until the gummed section is moved into position over the crease or fold in the flap of the envelope, where it is pressed down and held against the envelope and then snipped at each end thereof. The envelope carrier moves forward until another envelope is in position and the thread arm moved over to again grip the thread or cord and so on.

Having now particularly described and ascertained the nature of my said invention and in what manner the same is to be performed, I declare that what I claim is:

1. In improvements in or relating to envelope machines and the like, means for applying gum or other adhesive liquid to a section of a thread or cord to be inserted in the crease of the envelope as it passes from the reel on which it is wound, through a tensioning device consisting of a bath containing said adhesive liquid, a gumming bar pivotally carried and arranged to dip into said adhesive liquid and to be raised and pressed against the underside of said thread or cord, presser feet linked to said gumming bar and arranged and operated so as to press said thread against said gumming bar, said gumming bar being operated by a rod, lever, and cam from the operative part of said machine, as and for the purposes herein set forth.

2. In improvements in or relating to envelope machines and the like, a thread carrier consisting of a vertical spindle carried in bearings and capable of certain partially rotatable movements, an arm secured on said spindle, a pin on said arm engaging a cam track in a carriage operated by lever and cam, said cam being rotated by means from power supply, a pair of bosses on said spindle, a sheave on a stem carried in one of said bosses, said sheave being normally kept in a lowered position by a spring, a jaw on a stem carried in the other of said bosses, a disc slidably carried on said spindle, a lever, tappet, and cam for operating said disc, said cam being operated by power supply, as and for the purposes herein set forth.

3. In improvements in or relating to envelope making machines and the like, means for drawing a thread or cord into position over the crease of the fold of an envelope con-

sisting of a carriage slidably carried in guides and slidably operated by a lever, cam and shaft driven from a source of power supply, a thread arm arranged to be projected across the envelope from end to end, a fixed hooked jaw on the end of said arm, a movable jaw on the end of a stem slidable in said thread arm, said movable jaw being arranged to co-act with said fixed jaw, a spring actuating on said stem, a projection on said stem, a fixed stop position so as to make contact at certain times with said projection, as and for the purposes herein set forth.

4. In improvements in or relating to envelope machines and the like, means for securing a gummed thread into the crease of the fold of the envelope and severing said thread when secured, consisting of a lever formed so that the end thereof may be caused to press on said thread, a cam for operating said lever, said cam being carried on a staff operated from power supply, scissors mounted on levers on each side of the carriage, said lever being pivotally carried and operated by cams on shafts, said scissors being articulated to links hinged to a fixed part of the machine, as and for the purposes herein set forth.

5. In improvements in or relating to envelope machines and the like, means for controlling the operation of the machine at certain times consisting of a cam operated tappet, a recoil spring on said tappet, a light spring carried by said tappet and supporting a lever carried on a shaft pivotally carried on said machine at the side of said envelope carrier, a lever on said shaft and an inverted V groove on the end of said lever arranged to dip over an envelope carrier, a sector plate carried by said shaft, a cam face on said plate, a lever operated by said cam face, and articulated to a slide having a hole therein, said holed slide plate being interposed between a tappet and lever forming part of the means for operating the thread holder as claimed in claim 2, as and for the purposes herein set forth.

In testimony whereof I affix my signature.
CHARLES WALTER PETTMAN.
